UNITED STATES PATENT OFFICE.

MINOR E. CHAMBERLAIN, OF LEBANON, MISSOURI.

METALLIC LATH.

1,190,725.

Specification of Letters Patent. Patented July 11, 1916.

Application filed October 4, 1915. Serial No. 53,925.

To all whom it may concern:

Be it known that I, MINOR E. CHAMBERLAIN, a citizen of the United States, residing at the city of Lebanon, county of Laclede, and State of Missouri, have invented a new and useful Metallic Lath, of which the following is a specification.

This invention relates to improvements in metallic laths for use on reinforced concrete construction and for supporting plaster and the like.

An object of the invention is to provide an improved lath preferably composed of sheet metal folded to form oblique flanges on its side edges for the purpose of providing engaging portions for the concrete or plaster, whereby secure bonding engagement will be effected to hold the concrete or plaster.

Another object is to provide a lath of the character and for the purpose mentioned, in combination with improved spacing and clamping devices for securing the laths to their supports.

Other objects not requiring specific mention will appear from the following detailed description, reference being made to the accompanying drawing in which I have illustrated a preferred embodiment of the invention and in which—

Figure 1 is a sectional view of a wall structure having my improved laths embodied therein. Fig. 2 is a detailed view illustrating the laths in side elevation. Fig. 3 is a sectional view on the line 3—3 of Fig. 1, illustrating the concrete or plaster engaging the laths. Fig. 4 is a perspective view illustrating one of the laths secured to its support. Fig. 5 is a detailed view illustrating the construction of one of the laths and particularly illustrating the extended tongue or projection on one end and the slot on the opposite end which constitute means for securing the laths together in longitudinal series. Fig. 6 is a side elevation of the lath illustrated in Fig. 5. Fig. 7 is a cross sectional view on the line 7—7 of Fig. 5. Figs. 8 and 9 are detailed views illustrating the devices for securing the laths to their supports.

In the embodiment illustrated in Figs. 1 and 3, there is a wall structure composed of two parallel wall faces. The wall structure comprises a number of studs, each of which is composed of a section of sheet metal fold-

ed to provide a wing 1 of double thickness 55 and two wings 2 of single thickness of the sheet. The studs are arranged in pairs with the wings 1 of double thickness extending toward each other and the wings 2 being parallel with the surfaces of the wall. The 60 wings of double thickness of each pair of studs are reinforced and braced by connecting plates 3 which are spaced to receive the wings 1 as illustrated in Figs. 1 and 4, and the ends of which abut against the wings 2. 65 The wings 2 constitute supports for the laths and for the lath-securing devices, so that after the laths have been secured in connection with the studs the concrete or plaster may be applied to complete the wall. 70

The laths 4 are of novel construction and are preferably, though not essentially, composed of sheet metal. The side edges of each lath are folded obliquely toward each other to provide oblique flanges 5 between 75 and upon which the concrete or plaster may engage when applied. The flanges 5 are between the studs and across the face of the studs, and the edges of the sheet metal are folded flat upon the central portion thereof 80 as indicated at 6. Between the flat portions 6 and the flanges 5 the edges of the sheet metal are shaped to provide flaring portions 7 for better engagement with the concrete or plaster. Also at suitable intervals the lath 85 may be provided with holes or perforations 8 of sufficient size to permit portions of the concrete or plaster to be pressed therethrough and to engage upon the inner side of the lath, thus providing gripping extensions 90 for the concrete or plaster. Each lath is also preferably provided with a tongue 9 at one end and with a slot 10 at the opposite end so that the tongue 9 of one lath may be passed through the slot 10 of the adjacent 95 lath and clamped, thus securing the laths together in longitudinal series. The devices for securing the laths to the studs comprise plates 11 adapted to bear against the surfaces of the wings 2 of the studs and being of 100 sufficient length so that the ends thereof may be folded to clamp upon said wings 2 and thus secure the plates 11 in engagement with the studs. Each plate 11 is provided on its side edges with shouldered flanges 12 which 105 receive the flat portions 6 of the laths and thereby rigidly bind the laths in connection with the studs. By means of these devices

the laths may be secured to the studs in parallel series in position for the application of the concrete or plaster, which may be applied by use of the usual implements for such purposes, such as trowels or the like. The wall formed in this manner includes two separate wall faces, as illustrated in Figs. 1 and 3, each of which is supported upon a separate or distinct series of laths secured to a separate or distinct series of studs, and it will be noted that the studs of one series are connected with the studs of the other series so that the two wall faces may be rigidly supported with respect to each other. The plaster or concrete applied to the laths becomes bonded therewith by the hardening action of the plaster or concrete and, by engaging in the spaces formed by the flanges 5, forms a strong union. The flanges formed 20 on the side edges of the laths reinforce or strengthen the laths between the studs so that the laths do not easily bend or press inwardly under the pressure of the plaster or concrete when being applied thereto. The laths may thus be composed of comparatively thin sheet metal and yet be sufficiently rigid so that they will not yield or bend during the application of the concrete or 25 plaster, but will constitute comparatively 30 rigid elements which form a superior support for the wall material.

It will be understood that the structure may be varied in many particulars without departure from the principles of the invention and that I do not restrict myself to identical features of construction, but contemplate such variations as may be within the scope of the appended claims.

What I claim and desire to secure by Letters Patent of the United States, is:—

1. A metallic lath comprising a section of sheet metal having a substantially flat back surface and having its edges folded to provide flange portions on the outer side of the section of sheet metal, and said flange portions having parts thereof pressed flat against the outer surface of the sheet metal section. 45
2. A metallic lath comprising a section of sheet metal having its side edges folded to provide outwardly extending flanges and having portions of said flanges pressed flat against the outer surface of the sheet metal section, and said section having holes there-through between the flanges on opposite 50 sides thereof.
3. In a structure of the character described, series of metallic laths each being composed of a number of sheet metal sections arranged end to end, an interlocking tongue and slot connection holding the sheet metal sections of each series together end to end, and each of said sections being folded to provide outwardly extending flanges on the upper and lower edges thereof and having portions of said flanges pressed flat 55 against the outer surface of the sheet metal sections. 60

In witness whereof, I have signed this specification in the presence of two subscribing 70 witnesses.

MINOR E. CHAMBERLAIN.
